UNITED STATES PATENT OFFICE

WALTER J. HAAG, OF DAYTON, OHIO, ASSIGNOR TO THE BROWNELL COMPANY, OF DAYTON, OHIO, A CORPORATION OF OHIO

STOKER

Application filed November 10, 1928. Serial No. 318,525.

My invention relates to stokers, and in particular to underfeed stokers.

It is the object of my invention to provide means of applying air to the central portion 5 of the fuel bed of a fire box, particularly in connection with underfeed stokers.

It is my object to apply air, under pressure, at such points that are not ordinarily reached by the tuyères that surround the 10 margins of the coal bed through which air is normally delivered.

It is my object to provide a uniform burning of the bed of coal throughout its entire surface rather than at the margins, as is now 15 the case.

Referring to the drawings:

Figure 1 is a vertical section through the bottom of a furnace, and through the fuel retort, tuyères, etc.

20 Figure 2 is a section on the line 2—2 of Figure 1.

Referring to the drawings in detail, 1 and 2 indicate the front and rear walls supporting the boiler structure 3. The retort is designated 4. Fuel is delivered by the screw 5 into the retort at the bottom and one end thereof through the pipe 6. The other end of said retort is dome shaped. Air under pressure is delivered through the pipe 7 to the 25 chamber 8, around and below the retort whence it normally passes upwardly through the tuyère openings 9 in the tuyère casting 9' into the sides of the fuel. The tuyère casting is supported on the transverse members 30 10. 11 designates the usual dead plates upon which the ashes rest.

It will be observed there has been no means of delivering air heretofore to the center of the fuel bed. I have provided a transverse 40 longitudinally arranged tube 12 forming an air passageway, which communicates with the openings 13 in the side walls of the retort for admitting air under pressure. This air is discharged through stoker openings arranged 45 along the top of this air tube 12. Such openings are designated 14. The tube 12 forming an air passageway is located in the walls of the retort below the tuyère casting 9', and since the air openings in this tube are in the 50 top thereof combustion cannot take place in

the immediate vicinity of the body of the tube 12. This tube is therefore protected from the heat of the burning fuel.

In cross section this air delivery means is streamlined in order to provide for the 55 ready passage of fuel around it. Thus the retort is strengthened, the fuel is uniformly consumed throughout the entire surface, and great economies in fuel consumption are effected as unburned fuel cannot be forced 60 upwardly and laterally onto the dead plates 11 prematurely before its consumption.

I desire to comprehend within my invention such modifications as may be clearly embraced within my claims and the scope of 65 my invention.

Having thus fully described my invention, what I claim is new and desire to secure by Letters Patent, is:

1. In a furnace structure having walls 70 forming an air chamber, transverse members in said chamber, a retort in said chamber, an air tube in said retort and supported thereby and having air connections with said chamber, a tuyère casting on said retort and supported by said transverse members, means for feeding fuel into said retort, and means for forcing air into said air chamber, said air tube and tuyère casting having tuyères there- 75 in for conducting air from the air chamber 80 into the fuel.

2. In a furnace structure having walls forming an air chamber, the front and the rear walls having a ledge thereon, a transverse member adjacent each ledge, a tuyère 85 casting supported by the transverse members, and a dead plate supported by each ledge and the adjacent part of the tuyère casting.

3. In a furnace structure having walls forming an air chamber, the front and the rear walls having a ledge thereon, a transverse member adjacent each ledge, a tuyère casting supported by the transverse members, a dead plate supported by each ledge and the adjacent part of the tuyère casting, a retort in said air chamber beneath the tuyère casting, an air tube in said retort having air connections with said air chamber, said air tube and tuyère casting having tuyères there- 90 95 100

in, and means for forcing air into said chamber through said tuyères.

4. In a furnace structure, in combination walls having transverse ledges thereon and forming an air chamber, a retort in said chamber, a transverse member adjacent each ledge, a tuyère casting supported by the transverse members and resting upon the retort and a dead plate supported by each ledge and the adjacent part of the tuyère casting.

In testimony whereof, I affix my signature.

WALTER J. HAAG.
